UNITED STATES PATENT OFFICE.

ALBERT H. LA FORTUNE, OF HILTON, NEW JERSEY, ASSIGNOR TO GENERAL OPTICAL COMPANY, INC., A CORPORATION OF NEW YORK.

EDGE-GRINDING MACHINE.

1,324,454.

Specification of Letters Patent.

Patented Dec. 9, 1919.

Application filed February 12, 1916. Serial No. 77,827.

To all whom it may concern:

Be it known that I, ALBERT H. LA FORTUNE, a citizen of the United States, residing at Hilton, in the county of Essex and 5 State of New Jersey, have invented certain new and useful Improvements in Edge-Grinding Machines, of which the following is a full, clear, and exact description.

This invention relates to machines for 10 grinding the edges of lenses to produce a lens of the proper size and shape. The primary object of my invention is to provide an edge-grinding machine which may be used for grinding lenses of all shapes and 15 sizes, such as round, oval and "Boston" shaped lenses without requiring the pattern to be changed each time a different shape lens is to be cut.

Another object of the invention is to provide 20 an edge-grinding machine in which the pattern or former is not easily worn or mutilated and the lenses are always accurately ground.

With these and other objects in view, the 25 invention comprises a former or pattern for controlling the oscillatory movement of the lens holder in accordance with the shape of the lens to be ground, which former is driven at a speed synchronous to the speed 30 of the lens holder. The pattern or former is of a variable shape in cross section, the various cross sections corresponding to the various shapes to which it is desired to grind a lens, as for example, oval, round and 35 "Boston" shape. A contact member bears against the pattern and either the contactor or former is connected to the oscillatory lens holder to control the bodily movement thereof. The contactor is adjustable longitudinally of the former and the lens ground 40 will correspond in shape to the peripheral contour of the cross section of the former at its point of engagement with the contactor. In the preferred construction, the contactor is also adjustable laterally, which permits a lens of any desired size to be cut.

In one practical construction, the lens holder and former are rotatably mounted on a swinging frame in axial alinement. The 50 frame is maintained under a tension which urges the former against a relatively stationary contactor so that as the former revolves the swinging frame and hence the lens holder will have an oscillatory movement imparted to it which corresponds to the

contour of the surface of the former on the line traced by the contactor. The contactor is adjustable in a direction parallel to and normal to the axis of the former and thus the shape and size of the lens may be varied 60 at will.

The character of the invention may also be understood by reference to the following description of an illustrated embodiment thereof shown in the accompanying drawings, wherein—

Figure 1 is a plan of a machine constructed in accordance with the principles of my invention;

Fig. 2 is a side elevation thereof; 70

Fig. 3 is a detail of the slide which carries the contactor;

Fig. 4 is a section of Fig. 3 taken on the line 4—4;

Fig. 5 is a detail showing the former; 75

Figs. 6 and 7 are end views thereof; and

Figs. 8, 9, 10, 11 and 12 are sections of the former taken on the lines a—a, b—b, c—c, x—x, and y—y, respectively.

Referring to the drawings, the machine is 80 shown as supported upon legs 1 which carry a hollow bed or frame 2 which provides a chamber for the grind-stone 3. Carried by the bed 2 are two spaced parallel bed plates 4 and 5 which extend the entire length of the 85 machine and are connected at one end by a narrow strip 7. Bearings 8 and 9 are mounted upon the bed plates 4 and 5, respectively, which support a shaft 10 extending transversely of the frame and projecting through 90 both the bearings. Rigidly mounted upon one of these projecting ends is a pulley 11 which is adapted to be driven from a suitable source of power. The grind-stone 3 is mounted upon the shaft 10 between two collars 11 so that the grind-stone rotates with 95 the shaft. One of these collars carries a sleeve 12 which has a loose ring 12' mounted thereon to which is secured an arm 13 which is adapted to be oscillated and slowly move 100 the shaft 10 and the grind-stone 3 longitudinally of its axis as will be hereinafter referred to. Mounted in the bearing 9 is a sleeve or hollow shaft 14 which carries a worm gear 15. The shaft 10 passes through 105 this shaft 14 and the worm gear 15, these parts being keyed to the shaft so as to rotate therewith, and yet permit the shaft to slide longitudinally within the same. The hollow shaft 14 is provided with a collar or flange 110

14' which rotates in a suitable recess in the bearing and prevents any longitudinal movement of the worm 15 when the shaft 10 is reciprocated as described. The worm gear 15 meshes with a gear 16 mounted for rotation on a shaft 17 which extends along one side of the frame of the machine, and is supported in depending bearings 18, carried by the under face of the bed plate 5. The shaft 17 carries a worm 19 which meshes with a worm wheel 20, which is carried by a vertically disposed stud 20' secured to the bed plate 5 by means of a screw 21. The gear or worm wheel 20 extends through a suitable opening 22 in the bed 2 of the machine so that it will mesh with the gear 19.

The oscillating lever 13 is connected to the worm wheel 20 by a connecting rod 23 which is eccentrically pivoted to the worm 20, the amount of eccentricity controlling the travel of the grind-stone. The arm 13, as is shown in Fig. 2, has a yoke-shaped part 25 which carries a ring 12' which fits into a groove in the clutch sleeve 12. Extending from the yoke-shaped piece is a vertically disposed part 26 having a horizontal extension 27 which is pivoted to a flange 28 carried by the bed or frame of the machine.

Mounted upon the front ends of the two bed plates 4 and 5 is a base plate 30 which carries the entire mechanism of the machine other than the grind-stone and connections described. This base plate is provided with lugs 29 on its under face at its front edge and shorter lugs 28 at its rear edge which maintain the base plate in a slightly inclined position so that the water and dirt occasioned by the grinding of the lenses will tend to slide off the base plate into the chamber in the bed 2 and thus keep the plate comparatively clean.

Mounted upon the base plate, adjacent the side edges thereof, are bearings 31 which support a shaft 32 which extends transversely across the base plate. One end of this shaft projects beyond its bearings and carries a spiral gear 33 which is positioned over the shaft 17 and is adapted to mesh with a spiral pinion 34 carried by this shaft. The pinion 34 is loosely mounted between two collars 35, which are secured to the shaft 17 by set screws 36, or in any other desired manner, so that the collars may be moved along the shaft to bring the gear pinion 34 to any desired position thereon. This is necessary since the base plate 30 is adapted to move as a whole, toward and away from the grind-stone, as will be hereinafter referred to, which makes it necessary to provide means for moving the pinion 34 on the shaft 17 so that it may remain in mesh with the gear 33. Mounted upon the shaft 17 is a clutch member 37 carrying pins 37', which are adapted to pass through one of the collars 35, and engage with the pinion 34 and

thereby couple the pinion to the shaft 17. This clutch is adapted to be manually manipulated by the operator of the machine when it is desired to start or stop operation of the machine, as will be later described. Mounted upon the shaft 32 is a sleeve 38 which extends substantially the entire length thereof, and is provided with a plurality of curved arms. The arms which have been designated 38^a and 38^b, have bearings formed in their upper end for a shaft 39, while the arms 38^c and 38^d support a shaft 40 in coaxial alignment with the shaft 39.

The shafts 39 and 40 carry chucks 41 and 42 at their abutting ends, between which a lens 43 is adapted to be held; or in other words, the chucks 41 and 42 form the lens holder for the lens to be ground, and the sleeve 38, together with its arms or brackets, forms a swinging frame. To remove the lens, the shaft 40 is adapted to slide longitudinally within its bearings, and has a collar 45 mounted thereon against which a spring 46, surrounding the shaft, is adapted to bear at one end, the other end of this spring abutting against the bearing arm 38^d, so that the spring tends to force the chuck 42 against the chuck 41 to hold the lens in position. The shaft 40 is moved against the tension of this spring by an arm 48 which co-operates with the collar 45. Rigidly mounted upon the end of the shaft 40, which extends beyond the bearing 38^d, is a gear 49 which is adapted to mesh with a pinion 50 carried by the shaft 32. To permit the gear 49 to slide with the shaft 40, the pinion 50 is made of considerably greater width so that at each end of the movement of the shaft 40, the gear 49 will still be in mesh with this pinion. Mounted upon the shaft 32 adjacent its other bearing is a similar pinion 55 which meshes with a gear 56 carried by the shaft 39. Gears 50 and 55 are of the same pitch and diameter as gears 49 and 50, so that the co-axial shafts 39 and 40 will be driven in the same direction and at the same speed, the direction of rotation of the lens holders and the lens 43 being in a direction opposite the direction of rotation of the grind-stone 3. A spring 57 is secured to the swinging frame which supports the co-axial shafts 39 and 40, as for example, to the arm 38^c and at its other end is secured to some stationary part of the machine, which spring 57 exerts its tension to force the frame, and hence the lens holders carried thereby against the grind-stone.

Thus far described, the machine in general is similar to edge-grinding machines of a known type, and heretofore it has been the usual practice to provide means on one of the co-axial shafts 39 or 40 for placing a pattern or former in axial alignment with the lens, which pattern is adapted to bear

against a relatively stationary part which might be adjusted to vary the size of the lens, but not its shape. The main drawback to such machines has been the necessity of changing the pattern and substituting a new one each time a lens of a different shape is to be ground, which change requires a considerable period of time, and hence, increases the expense of grinding the lens.

5 Moreover, errors are frequently made, due to the selection of the wrong pattern, or to the improper adjusting of the pattern, which will result in a lens being inaccurately ground.

10 In my machine, I dispense with all chucks necessary for holding such patterns, and in place of a set of individual patterns which have heretofore been deemed necessary, I use a former 60 which is permanently mounted for rotation upon the shaft 39. This former is shown in detail in Figs. 5 to 12, inclusive, and is so shaped that the peripheral contour of the various cross sections thereof corresponds to the various 25 shaped lenses to be cut as, for example, at one end the former is of a narrow elliptical shape which corresponds to the narrowest lenses which are used. The minor axis of the ellipse then increases in length 30 as shown by cross sections in Figs. 8, 9 and 10, until the line $d-d$ is reached, at which point a cross section of the former is a perfect circle. The remaining section of the former is shaped so that the peripheral 35 contours of its cross sections correspond to the shape of the lenses known as "Boston" lenses, which are shown in Figs. 7, 11 and 12. The surface of the former intermediate the sections indicated forms a smooth curve 40 and it is obvious that the shape of the former at any intermediate cross section will be slightly different than those shown, thereby giving practically an infinite number of shapes to which a lens may be ground.

45 As described, the former is mounted in the tensioned swinging frame and hence it is held against a contactor 61 which consists of a blade having a round point 62 engaging the surface of the former. The contactor is 50 mounted upon three pins 63, 64 and 65 which pass through openings therein and are supported in two spaced upright standards 66. The pin 65 is rotatable and is threaded its entire length to engage in a 55 correspondingly threaded opening in the contactor so that by rotating this screw, the contactor may be moved laterally so as to engage the former at any desired point on its periphery. The shaft 65 is provided 60 with a thumb knob 67 to manually rotate the same. Extending across the standards 66 is a scale 68 with which a pointer 69 carried by the contactor co-operates to indicate the peripheral contour of the section engaged by the contactor.

The standards 66 converge at their lower ends and are secured to or form an integral part of a sliding plate 70 mounted in grooves or slide-ways 71 in the base plate (see Fig. 4), and protected by a cover 72. 70 The sliding plate carries a lug 74 on the underside of its front end which is provided with a screw-threaded opening through which a threaded shaft 75 passes. This shaft is mounted upon the base plate in suitable bearings and has one end thereof extending exteriorly of the front edge of the machine and provided with a thumb knob 76 whereby upon rotation of the threaded shaft 75 the sliding plate 70 will be advanced toward or withdrawn from the grind-stone; or in other words, the length of the path of the former and the swinging frame will be varied and the size of the lens which is ground varied accordingly. The 80 threaded shaft 75 carries a worm 77 which engages a worm gear 78 mounted on a vertically disposed stud in the cover plate 72, the upper end of this stud carrying a pointer 79 which is adapted to co-operate with a 85 scale 80 to indicate the size of the lens which is being ground.

The entire base plate and the operating mechanism which it supports is slidably mounted upon the bed plates 4 and 5, which 90 bed plates are slotted as at 81 to receive bolts 82 which pass upwardly through the slots into a portion of the base plate whereby the base plate may be moved toward or away from the grind-stone and clamped at any 95 desired position.

The operation of the machine is obvious from the description, but will be briefly described. Assuming that the pulley 11 is being driven, the grind-stone will be rotated 100 and through the worms 15, 16, 19 and 20, and the other connections the grind-stone will receive a slow reciprocatory movement in a direction transverse to the machine. While the machine is being made ready, the 105 clutch 37 should be thrown out so that the pinion 34 will not actuate the gear 33 to rotate the shafts 39 and 40 carrying the lens holder and other parts. The lens is inserted between the chucks 41 and 42 by throwing 110 the lever 48 to the right. After the lens has been properly positioned, the contactor 61 is set by the thumb knobs 67 and 76 to engage with the former at the desired section thereof. In other words, the thumb knob 67 115 is rotated until the contactor is moved laterally until the pointer and scale indicate that it is engaging a section of the former whose peripheral contour corresponds to the shape of the lens to be cut. In the same 120 manner the thumb knob 76 is rotated until the pointer 79 indicates upon the scale 80 the desired size of the lens. The spring 57 urges the lens holder and other parts carried by the swinging frame toward the grind-stone 125 130

and if the clutch 37 is now thrown in, the lens will be rotated in the opposite direction to the grind-stone and the edge of the lens will commence to be ground. At this time, 5 the contactor may or may not be in engagement with the former, but as the grinding action continues, the contactor will come into engagement with the former at different points during the rotation until finally 10 the contactor remains in engagement with the former during the entire rotation of the lens, and the lens will thus be ground to a shape exactly corresponding to the peripheral contour of the section of the former 15 which is engaged by the contactor, the oscillatory movement imparted to the swinging frame being similar in all respects to the oscillatory movement which is imparted to the lens holder in the types of machine now 20 generally in use. To grind lenses of any other shape and size it is only necessary to adjust the contactor both laterally and normally to the former, the indicators described informing the operator when the machine is 25 properly set for the desired shaped lens.

I claim:

1. In an edge grinding machine for lenses, a grinder, a rotary lens holder, and means for imparting an oscillatory movement to 30 said lens holder toward and away from the grinder comprising a former fixed to rotate with the lens holder and a contactor adapted to engage the surface of said former, said former and contactor being relatively adjustable by relative movement longitudinally of the axis of said former, said former having a surface, the contours of the various cross sections of which correspond to the contours of a plurality of different 35 shaped lenses.

2. In an edge grinding machine for lenses, a grinder, a rotary lens holder, and means for imparting an oscillatory movement to said lens holder toward and away from the 40 grinder comprising a former fixed to rotate with the lens holder and a contactor adapted to engage the surface of said former, said former and contactor being relatively adjustable by movement both longitudinally and normally to the axis of said former, said former having a surface, the contours of the various cross sections of which correspond to a plurality of contours of the different shaped lenses.

3. In an edge grinding machine, a grinder, a rotary lens holder, and means for imparting an oscillatory movement to said holder toward and away from the grinder comprising a former fixed to rotate with said holder 45 and a contactor adapted to engage the surface of said former and to be adjusted longitudinally with respect to said former, said former having a surface, the contours of the various cross sections of one smooth uninterrupted portion of which vary gradually 50 to a plurality of contours of the different shaped lenses.

from a narrow ellipse to a perfect circle, said former having another smooth uninterrupted part of its surface, the various cross sections of which correspond in shape to the shape of a "Boston" lens.

4. In an edge grinding machine for lenses, a grinder, a rotary lens holder, and means for imparting an oscillatory movement to said lens holder toward and away from the grinder, comprising a former and a contactor adapted to engage the face of said former, a sliding plate carrying said contactor and adapted to be moved in a direction normal to the axis of the former, a contactor carried by said sliding plate and adapted to be moved on said plate in a direction parallel to the axis of said former, said former having a surface, the contours of the various cross sections of which correspond to the contours of a plurality of different shaped lenses.

5. In an edge grinding machine for lenses, a grinder, a rotary lens holder, means for imparting an oscillatory movement to said lens holder toward and away from the 90 grinder, comprising a former and a contactor adapted to engage the face of said former, a sliding plate carrying said contactor and adapted to be moved in a direction normal to the axis of the former, a contactor carried by said sliding plate and adapted to be moved on said plate in a direction parallel to the axis of said former, said former having a surface, the contours of the various cross sections of which correspond to the contours of a plurality of different shaped lenses.

6. In an edge grinding machine for lenses, a rotary lens holder comprising two chucks, rotary shafts carrying said chucks, one of said shafts being movable longitudinally of its axis, a former carried by the other of 105 said shafts in axial alinement with said shafts, said former having the contours of the various cross sections thereof corresponding to the contours of the various shaped lenses to be cut, a sliding plate movable normally to said former, spaced standards carried by said plate, pins connecting said standards, a contactor slidably mounted on said pins, means for moving said contactor on said pins to engage different portions of the surface of said former, and means for moving said sliding plate.

7. In an edge-grinding machine for lenses, a grinder, a rotary lens holder and means for imparting an oscillatory movement to 120 said lens holder toward and away from the grinder comprising a former fixed to rotate with the lens holder, and a contactor adapted to engage the surface of said former thereby to limit the position of the holder relative to the grinder, the said former and contactor being relatively movable longitudinally of the axis of said former, said former having an uninterrupted smooth surface, the contours of the various cross sec- 125 130

tions of which correspond to the contours of a plurality of different shaped lenses.

8. In an edge-grinding machine for lenses, a grinder, a rotary lens holder, and means for imparting an oscillatory movement to said lens holder toward and away from the grinder comprising a former fixed to rotate with the lens holder and a contactor adapted to engage the surface of said former there-
10 by to limit the position of the latter relative to the grinder, said former and contactor being relatively movable longitudinally of the axis of said former, means for anchoring the former and contactor in con-

tact with one another at any position relative to the longitudinal axis of the former, said former having an uninterrupted smooth surface, the contours of the various cross sections of which correspond to the contours of a plurality of different shaped 15 lenses.

In witness whereof, I subscribe my signature in the presence of two witnesses.

ALBERT H. LA FORTUNE.
